UNITED STATES PATENT OFFICE.

HENRY C. TEIPEL, OF PARIS, ILLINOIS.

AUDITORIUM-SEAT.

1,196,614.

Specification of Letters Patent. Patented Aug. 29, 1916.

Application filed October 4, 1915. Serial No. 53,997.

To all whom it may concern:

Be it known that I, HENRY C. TEIPEL, a citizen of the United States, residing at Paris, in the county of Edgar and State of Illinois, have invented certain new and useful Improvements in Auditorium-Seats, of which the following is a specification.

This invention relates to seats for theaters, music halls and like places of public assembly, and its object is to movably mount the rows of seats and to provide a means whereby one row of seats may be moved forward and the next row to rear moved back, thereby increasing the distance between said rows sufficiently to enable patrons to enter or leave their seats without the necessity of the other occupants rising, folding up their seats and moving back.

The object stated is attained by means of a novel combination and arrangement of parts to be hereinafter described and claimed, reference being had to the accompanying drawing, in which—

Figure 1 is a side elevation showing the application of the invention; Fig. 2 is a front elevation, and Fig. 3 is a detail in plan view.

Referring specifically to the drawing, 5 denotes a row of seats, and 6 another row 30 behind the same. Adjacent to the ends of the row 5 of seats, bearings 7 are mounted on the floor 8 of the auditorium containing the seats. In these bearings is supported a rock shaft 9 which extends beneath the seats, 35 close to the floor. To one end of the rock shaft is fixed a rocker arm 10 having a hand lever extension 11 rising to a suitable height alongside the seat at this end of the row, and on the other end of the rock shaft is 40 fixed a rocker arm 12 which is alongside the seat at the corresponding end of the row. The row of seats is movably supported on the floor 8, being provided with rollers 13 to facilitate their travel. All the seats of the 45 row are connected so that they move as one. The rock shaft extends parallel to the row of seats or in the direction of the length of the row, and hence, when the shaft is rocked in the proper direction and the arms 10 and 50 12 are coupled to the end seats of the row, the entire row is moved forward from the next row 6 behind the same.

The following means are provided for coupling the rocker arms 10 and 12 to the 55 end-seats of the rows: Each rocker arm has an outstanding pin on one side, the pin of

the arm 10 being shown at 14 and the pin of the arm 12 at 15. The arm 10 is on the outside of the adjacent end seat, and the arm 12 is adjacent to the inner face of the side casting of the other end seat, said seat side having an aperture 16 to receive the pin 15, and the side casting of the first-mentioned seat having an aperture 17 for the pin 14. The pins are in alinement with the respective apertures, and the shaft 9 is 60 slideable in the direction of its length. Hence, when the hand lever 11 is forced inward toward the adjacent end seat, the shaft is slid 65 in a direction to carry the coupling pins into the seat apertures, and upon swinging the lever, the row of seats is shifted as hereinbefore described.

The parts hereinbefore described associated with the row 5 are duplicated for 75 the row 6, as well as the other rows of seats, and in the drawing they are designated by corresponding reference characters primed.

Simultaneous with the shifting of the row 5 of seats forward, the next row 6 behind the 80 same is shifted rearward, the following means being provided for this purpose:

On the shaft 9, adjacent to the end seat opposite the hand lever 11, is loosely mounted a lever 18, one end of which has an outstanding side pin 19 which is opposite the pin 14 and on the opposite side of the seat, so that it is withdrawn from the aperture 17 when the pin 14 is inserted thereinto, and when the pin 14 is withdrawn, the pin 19 90 enters the aperture. Adjacent to the rocker arm 12, a lever 20 is loosely mounted on the shaft 9, said lever having a pin 21 designed to enter the aperture 16 when the pin 15 is withdrawn.

To the rocker arm 10 is connected one end of a link 22 which extends rearward and is connected at its other end to the lever 18 associated with the row 6 of seats. A link 23 connects the rocker arm 12 to the corresponding rocker arm associated with the row 6 of seats. Similar connections are provided between all the rows of seats.

In operation, when the hand lever 11 is pushed toward the end seat of the row 5, 105 the pin 14 enters the aperture 17, and the pin 15 enters the aperture 16, and at the same time the pins 19 and 21 are withdrawn from these apertures to unlock from the row 5 the next row 6. The rocker arms 10 and 12 are now coupled to the row 5 and 110 when the hand lever 11 is swung forward,

the row 5 is advanced as shown dotted in Fig. 1. At the same time, the link 22 is drawn forward and through the lever 18' (the pin 19' of which is seating in the aperture 17' of the end chair of the row 6), said row is pushed back as shown dotted in Fig. 1. The motion of the row 5 is also transmitted to the row 6 through the rocker arm 12 and the link connection 23 between said 10 arm and the corresponding arm of the row 6. This movement of the rows 5 and 6 is hardly perceptible because under ordinary conditions the addition of six inches will give an ample passageway, which means 15 that each row will travel but three inches.

The apertures 16 and 17 are elongated somewhat to accommodate the angular swing of the arms 10 and 12. This is also true with respect to the corresponding 20 apertures of the parts associated with the row 6 of seats. The levers 18 and 20 are side-pinned to the rock shaft 9 to move with the same when it is shifted in the direction of its length as hereinbefore described.

25 When the distance between the rows of seats is such that by moving any row five or six inches forward or back does not crowd the occupants, it may be advisable to have every other row stationary and the 30 other rows movable and equipped with shaft 9 and rocker arms 10 and 12 only, eliminating the operating connections between the rows, and requiring that only one-half of the rows be equipped. This arrangement leaves all the operating parts 35 above the floor 8.

Either type of apparatus can be operated from a central station or by ushers, and 40 push button buzzer, light, or other signals may be installed to advise central station or ushers when patrons desire to leave their seats.

The bearing 7 adjacent to the rocker arm 10 has a side notch 24 in which said rocker 45 arm seats when the same is disconnected from the row of seats, and it is thus held locked in this position.

I claim:

1. The combination of a row of movable 50 auditorium seats connected to move together relative to the next row of seats, and actuating means connected to said row for effecting such movement, said actuating means comprising a rock shaft extending

along the row of seats and movable in the 55 direction of its length, and an actuating lever fixed on the rock shaft and having means for operative connection to the row of seats, said lever being coupled to and uncoupled from the row of seats by the longitudinal movement of the rock shaft.

2. The combination with rows of auditorium seats, the seats of the respective rows being connected, and said rows being movably supported; of means for simultaneously shifting a row of seats forward and the next row behind the same rearward.

3. The combination with rows of auditorium seats, the seats of the respective rows being connected, and said rows being movably supported; of means for simultaneously shifting a row of seats forward and the next row behind the same rearward, 70 said means comprising a rock shaft extending along each row of seats, an actuating 75 lever fixed on the rock shaft, means for operatively connecting said lever to the row of seats, a lever fulcrumed on the rock shaft, means for coupling said lever to the row of seats, and a connection between the actuating lever of a row of seats and the lever of the next row behind the same for moving said row rearward when the row ahead 80 is moved forward.

4. The combination with rows of auditorium seats, the seats of the respective rows being connected, and said rows being movably supported; of means for simultaneously shifting a row of seats forward and the next row behind the same rearward, 85 said means comprising a rock shaft extending along each row of seats, an actuating lever fixed on the rock shaft, a lever fulcrumed on the rock shaft, means for alternately coupling said levers to the row of seats, the actuating 90 lever being uncoupled when the other lever is coupled, and vice versa, and a connection between the actuating lever of a row of seats and the lever of the next row behind the same for moving said row rearward 95 when the row ahead is moved forward.

In testimony whereof I affix my signature in presence of two witnesses.

HENRY C. TEIPEL.
